(Cl. D9—2)

To all whom it may concern:

Be it known that I, Charles E. Richardson, a citizen of the United States and a resident of South Gate, in the county of Los Angeles and State of California, have invented a new, original, and ornamental Design for a Dry Cleaners' Spot Removing Device, of which the following is a specification, reference being had to the accompanying drawing, forming a part thereof:

Fig. 1 is a perspective view of a dry cleaners' spot removing device showing my new design in which the dominant features of my design are shown in heavy lines;

Fig. 2 is also a perspective view showing the opposite faces of the device and;

Fig. 3 is an end elevational view.

I claim:

The ornamental design for a dry cleaners' spot removing device, substantially as shown and described.

CHARLES E. RICHARDSON.
